(57) **CLAIM**

The ornamental design for an electronic pendant, as shown and described.

DESCRIPTION

FIG. 1 is a perspective view of an electronic pendant, showing my design;

FIG. 2 is a front view of the electronic pendant;

FIG. 3 is an opposing rear side view of the electronic pendant;

FIG. 4 is a left side view of the electronic pendant;

FIG. 5 is an opposing right side view of the electronic pendant;

FIG. 6 is a top view of the electronic pendant; and,

FIG. 7 is an opposing bottom view of the electronic pendant.

The broken lines shown in FIGS. 1-7 are for illustrative purposes only and form no part of the claimed design.
